UNITED STATES PATENT OFFICE.

ADIEL Y. DODGE, OF SOUTH BEND, INDIANA, ASSIGNOR TO BENDIX BRAKE COMPANY, OF CHICAGO, ILLINOIS, A CORPORATION OF ILLINOIS.

BRAKE MECHANISM.

Application filed August 17, 1925. Serial No. 50,659.

This invention relates to brakes, and is illustrated as embodied in a "double-wrapping" or "duo-servo" automobile brake. An object of the invention is to provide improved means for positioning the brake shoes, and preferably including a novel expansion joint shifting in one direction or the other with the shoes according to the direction of drum rotation and shown in the form of a double cam between the ends of the shoes.

It will be seen that this constitutes a novel floating expansion joint, adjustable from outside the brake. While one embodiment only has been described, it is not my intention to limit the scope of the invention to that particular embodiment or otherwise than by the terms of the appended claims.

This and other features of the invention, including various novel combinations of parts and desirable particular constructions, will be apparent from the following description of one illustrative embodiment shown in the accompanying drawing, in which:

Fig. 1 is a vertical section through the brake, just inside the wheel, showing the shoes in side elevation; and

Fig. 2 is a horizontal section on the line 2—2 of Fig. 1, showing the novel expansion joint.

The particular brake shown includes a drum 10 and a backing plate 12, between which are arranged interchangeable shoes 14 and 16. Between the upper ends of the shoes is a floating cam 18, or other brake-applying means, and a stationary anchor 20, arranged to take the braking torque of both shoes from shoe 16 when the drum is turning clockwise, and from shoe 14 when the drum is turning counter-clockwise. The shoes are urged away from the drum by a spring or pair of springs 22.

Shoe 14 is urged, by a spring 24, against an adjustable eccentric stop 26 near its opposite end, while if desired a similar spring and stop 28 and 30 may be provided for shoe 16.

Between the lower or opposite ends of the shoes is an angularly-adjustable cam 32, carried by a floating bracket 34, and locked in any desired position of angular adjustment by a nut 36. The threaded end of the shaft portion of cam 32 projects through an opening or slot 38 in the backing plate, to permit the bracket to float as described, while a pin 40 carried by the backing plate

50 12 may project through a radial slot 42 in the bracket, to provide a floating pivotal connection.

A pair of posts 44 carried by backing plate 12 project through slots 46 in bracket 34, and through slots 48 in the shoes, thus

serving to guide the bracket and shoes. I prefer to mount on these posts a plate 50 serving as a steady rest to position the shoes laterally.

It will be seen that this constitutes a novel floating expansion joint, adjustable from outside the brake. While one embodiment only has been described, it is not my intention to limit the scope of the invention to that particular embodiment or otherwise than by the terms of the appended claims.

I claim:

1. A brake comprising, in combination, a drum, a plurality of floating shoes engageable with the drum and shifting to anchor on one shoe when the drum is turning in one direction and on the other shoe when the drum is turning in the other direction, and a floating joint connecting the shoes and including a cam between the ends of the shoes and a part rigid with the cam which is operable to turn the cam, the entire joint including the cam and said part being shiftable as a unit in either direction with the shoes.

2. A brake comprising, in combination, a drum, a backing plate, a plurality of floating shoes engageable with the drum and shifting to anchor on one shoe when the drum is turning in one direction and on the other shoe when the drum is turning in the other direction, and a floating joint connecting the shoes and including a cam between the ends of the shoes and a shaft rigid with the cam which is operable to turn the cam and which extends through a relatively large opening in the backing plate, the entire joint including the cam and said shaft being shiftable as a unit in either direction with the shoes.

3. A brake comprising, in combination, a plurality of shoes, an angularly-adjustable shaft having a cam between the shoes, means to lock the shaft in any desired position of angular adjustment, and means for supporting the shoes in such a manner as to permit the shaft and cam to float with the shoes.

4. A brake comprising, in combination, a drum, a plurality of floating shoes, an angularly-adjustable shaft having a cam between the shoes, means to lock the shaft in any desired position of angular adjustment, and means for supporting the shoes in such a manner as to permit the shaft and cam to float with the shoes.

manner as to permit the shaft and cam to float with the shoes, and means for taking the braking torque of both shoes from the other end of one of the shoes when the drum 5 is turning in one direction, and from the opposite shoe when the drum is turning in the other direction.

5. A brake comprising, in combination, a plurality of shoes, a cam between the ends of 10 the shoes, means to hold the cam in any position of adjustment, and spring means holding the shoes against the cam, the cam and said means being free to float as a unit with the shoes.

15 6. A brake comprising, in combination, a drum, a plurality of shoes, a cam between the ends of the shoes, means to hold the cam in any position of adjustment, spring means holding the shoes against the cam, the cam 20 and said means being free to float as a unit with the shoes, and means for forcing the opposite ends of the shoes against the drum.

7. A brake comprising, in combination, a drum, a plurality of shoes, a cam between 25 the ends of the shoes, means to hold the cam in any position of adjustment, spring means holding the shoes against the cam, the cam being free to float with the shoes, means for forcing the opposite ends of the shoes 30 against the drum, means for taking the braking torque from either of said opposite ends, and means for centering the cam and the adjacent shoe ends when the brake is released.

35 8. A brake comprising, in combination, a drum, a plurality of shoes, a cam between the ends of the shoes, means to hold the cam in any position of adjustment, spring means holding the shoes against the cam, the cam 40 being free to float with the shoes, means for forcing the opposite ends of the shoes against the drum, a stationary anchor between said opposite ends for taking the braking torque from either of them, and 45 means for centering the cam and the adjacent shoe ends when the brake is released.

9. A brake comprising, in combination, a drum, a plurality of shoes, means for forcing the ends of the shoes against the drum, 50 a pivoted bracket adjacent the opposite ends of the shoes, and an expansion joint for said opposite ends including an adjustable cam having a shaft journaled in the bracket.

55 10. A brake comprising, in combination, a drum, a plurality of shoes, means for forcing the ends of the shoes against the drum, a movable bracket adjacent the opposite ends of the shoes, and a double cam between the said opposite ends and carried by the 60 bracket.

11. A brake comprising, in combination, a drum, a plurality of shoes, means for forcing the ends of the shoes against the drum, a floating bracket adjacent the opposite ends 65 of the shoes, a double cam carried by the

bracket between said opposite ends and which is adjustable angularly to force said ends apart, and means for holding the cam in adjusted position.

12. A brake comprising, in combination, a 70 drum, a plurality of shoes, means for forcing the ends of the shoes against the drum, a radially and circumferentially movable bracket adjacent the opposite ends of the shoes, a double cam carried by the bracket 75 between said opposite ends and which is adjustable angularly to force said ends apart, means for holding the cam in adjusted position, and spring means holding the shoes against the cam. 80

13. A brake comprising, in combination, a drum, a plurality of shoes, means for forcing the ends of the shoes against the drum, a radially and circumferentially movable bracket adjacent the opposite ends of the 85 shoes, a double cam carried by the bracket between said opposite ends and which is adjustable angularly to force said ends apart, means for holding the cam in adjusted position, spring means holding the shoes against 90 the cam, and a stop cooperating with the spring to determine the idle positions of the shoes.

14. A brake comprising, in combination, a drum, a plurality of shoes, brake-applying 95 means and torque-taking means acting on the same ends of the shoes, a stop engaging one of the shoes near its opposite end, an expansion joint connecting the shoes, and springs normally holding the shoes in idle 100 positions determined by the torque-taking means and the stop and the expansion joint.

15. A brake comprising, in combination, a drum, a backing plate at the open side of the drum, shoes between the drum and 105 backing plate, and a floating expansion joint between adjacent ends of the shoes including a cam having an integral shaft passing through and adjustable from outside the backing plate. 110

16. A brake comprising, in combination, a drum, a backing plate at the open side of the drum, shoes between the drum and backing plate, and a floating expansion joint 115 between adjacent ends of the shoes including a cam between said ends and means passing through the backing plate for adjusting the cam and which floats with said cam and shoe ends.

17. A brake comprising, in combination, 120 a drum, a backing plate at the open side of the drum, shoes between the drum and backing plate, and a floating expansion joint between adjacent ends of the shoes including a cam having a shaft rigid therewith 125 and extending through a relatively large opening in the backing plate and adjustable from outside the backing plate.

18. A brake comprising, in combination, 130 a drum, a backing plate, shoes between the

drum and backing plate, a bracket pivoted on the backing plate, and an expansion joint for adjacent ends of the shoes carried by the bracket and adjustable from outside the

5 backing plate.

19. A brake comprising, in combination, a drum, a backing plate, shoes between the drum and backing plate, a bracket between the shoes and the backing plate and shift-
10 able with the shoes with respect to the back-
ing plate, and an expansion joint for ad-
jacent ends of the shoes carried by the
bracket.

20. A brake comprising, in combination, a pair of shoes having adjacent movable ends formed with openings, a support having a joint for said ends and parts projecting through the openings, and a member carried by said projecting parts, the shoe ends being
20 confined between the support and said member.

21. A brake comprising, in combination, a drum, a fixed anchor, a floating friction device within the drum having separable ends and anchoring on one of said ends against said anchor when the drum is turn-
25 ing in one direction and on the other of said ends against the anchor when the drum is turning in the other direction, and a pair of stops spaced approximately 120° on each side of said anchor and co-operating with said anchor in determining the released position of said friction device.

22. A brake comprising, in combination, a drum, a fixed anchor, a floating friction device within the drum having separable ends and anchoring on one of said ends against said anchor when the drum is turning in one direction and on the other of said ends
35 against the anchor when the drum is turn-
ing in the other direction, and a pair of stops spaced approximately 120° on each side of said anchor and co-operating with

said anchor in determining the released po-
sition of said friction device, at least one 45
of said stops being adjustable.

23. A brake comprising, in combination, a drum, a fixed anchor, a floating friction device within the drum having separable ends and anchoring on one of said ends 50 against said anchor when the drum is turn-
ing in one direction and on the other of said ends against the anchor when the drum is turning in the other direction, and a pair of stops spaced approximately 120° on each 55 side of said anchor and co-operating with said anchor in determining the released position of said friction device, at least one of said stops being an adjustable eccentric.

24. A brake comprising, in combination, a drum, a fixed anchor, a floating friction device within the drum having separable ends and anchoring on one of said ends against said anchor when the drum is turn-
60 ing in one direction and on the other of 65
said ends against the anchor when the drum is turning in the other direction, and a pair of stops spaced approximately 120° on each side of said anchor and co-operating with said anchor in determining the released 70 position of said friction device, said friction device including an adjustment for increas-
ing its effective length to compensate for wear.

25. A brake comprising, in combination, 75
a floating friction device having adjacent separable ends and provided with an adjust-
ment for increasing its effective length to 80
compensate for wear, applying and anchor-
ing means adjacent said ends, and stops ar-
ranged approximately 120° in opposite di-
rections from said ends.

In testimony whereof I have hereunto
signed my name.

ADIEL Y. DODGE.
